(57) **CLAIM**

The ornamental design for scissors, as shown and described.

DESCRIPTION

FIG. 1 is an enlarged perspective view of the scissors; FIG. 2 is another enlarged perspective view thereof; FIG. 3 is a front view thereof; FIG. 4 is a rear view thereof; FIG. 5 is a plan side view thereof; FIG. 6 is a bottom side view thereof; FIG. 7 is a right side view thereof; FIG. 8 is a left side view thereof; FIG. 9 is an enlarged cross-sectional view thereof at 9-9 of FIG. 3;

FIG. 10 is an enlarged cross-sectional view thereof at 10-10 of FIG. 3;

FIG. 11 is an enlarged cross-sectional view thereof at 11-11 of FIG. 3;

FIG. 12 is an enlarged cross-sectional view thereof at 12-12 of FIG. 3;

FIG. 13 is an enlarged cross-sectional view thereof at 13-13 of FIG. 3; and,

FIG. 14 is an enlarged cross-sectional view thereof at 14-14 of FIG. 3.

The broken line showing of the internal construction features in FIGS. 9-12 illustrates unclaimed portions of the scissors and forms no part of the claimed design.
